F. O. WHITE.
VENTILATED UPHOLSTERED FURNITURE.
APPLICATION FILED JULY 12, 1919.

Patented June 28, 1921.

INVENTOR
FRANK O. WHITE,
by Arthur C. Eckert, ATTORNEY.

UNITED STATES PATENT OFFICE.

FRANK ORMOND WHITE, OF BELLEVILLE, ILLINOIS.

VENTILATED UPHOLSTERED FURNITURE.

1,382,702.

Specification of Letters Patent. Patented June 28, 1921.

Application filed July 12, 1919. Serial No. 310,454.

To all whom it may concern:

Be it known that I, FRANK ORMOND WHITE, a citizen of the United States, and resident of Belleville, Illinois, have invented 5 certain new and useful Improvements in Ventilated Upholstered Furniture, of which the following is a specification containing a full, clear, and exact description, reference being had to the accompanying drawings, 10 forming a part hereof.

The object of my invention is to fabricate a seat and back for furniture which will be aerated, prevent the sticking of the user's clothing to the seat and the back of chairs, 15 lounges, etc., in warm weather.

In the conventional seat, the user in hot weather, due to perspiration, becomes very uncomfortable, particularly where he is compelled to remain in one seat for any considerable length of time. An automobile driver, 20 particularly where the limits of his bodily movements are small and where he drives for hours continually, becomes very uncomfortable in hot weather, owing to the lack 25 of air circulation in and around the seat and back.

My purpose is accomplished by providing an air space immediately under the seat and back whereby the air can pass, as well as a 30 perforated member, as cane or leather by which the air may pass from the air space to the person of the user.

With the above and other objects in view, my invention has relation to certain novel 35 features of construction and operation, examples of which are described in the following specification and illustrated in the accompanying drawings in which—

Figure 1 is a front elevation.
40 Fig. 2 is a side elevation, and
Fig. 3 is a plan.

Numeral 4 indicates a base plate and numeral 5 a seat element, held in spaced relationship by means of the supports 6; 7 45 designates a back plate and 8 a back element held in spaced relationship by means of the supports 9; 10 designates a spring fastened to the back plate at 11 and to the base plate at 12. This spring is of the conventional form holding the back plate normally 50 at right angles with the base plate, but permitting the back plate to be oscillated backward from its normal vertical position. In the seat element 5, is formed a reticulated 55 seat element 13 and in the back element 8,

is formed the reticulated back element 14. The external end of the seat element 5 is chamfered off, as is the back element 8. The seat element 5 is of smaller area than the base plate 4 and the back element 8 is of smaller area than the back plate 7. These reductions in area are made to prevent the catching of the clothing and to give the device a finished appearance. By these means, 60 air is permitted to circulate between the base plate 4 and the seat element 5 and pass through the reticulations in the reticulated seat element 13 to the person of the user of the seat; similarly air is permitted to circulate between the back element 8 and the 65 back plate 7 through the reticulations in the reticulated back element 14. The supports 6 and 9 terminate at the respective reticulated elements. These reticulated elements 70 may be made of any resilient material, such as perforated leather stretched taut, or cane. 75

I claim—

1. In furniture, a base plate and a seat element, said base plate and seat element secured in spaced relationship by means of 80 rigid supports, said seat element located concentric the base plate and of smaller area than said base plate, a back plate and a back element secured in concentric constant spaced relationship by means of rigid supports, said back element of smaller area than 85 said back plate element, said seat element and back element secured in operative relationship.

2. In a portable seat, a base plate and a 90 seat element, said base plate and seat element secured in substantially restricted spaced relationship by means of rigid supports, said seat element located concentric the base plate and of smaller area than said 95 base plate, a back plate and a back element secured in substantially restricted concentric constant spaced relationship by means of rigid supports, said back element of smaller area than said back plate element, said seat element and back element secured in operative relationship. 100

In testimony whereof I have signed my name to this specification, in presence of two subscribing witnesses.

FRANK ORMOND WHITE.

Witnesses:

PHYLLIS L. MUFFRAY,
WILLIAM HIRAM BAUER.
